UNITED STATES PATENT OFFICE.

ADOLPH WEBER, OF DETROIT, MICHIGAN, ASSIGNOR OF ONE-HALF TO
HENRY W. ROOD, OF SAME PLACE.

STRAIGHT-WAY-VALVE CASE.

SPECIFICATION forming part of Letters Patent No. 316,583, dated April 28, 1885.

Application filed November 26, 1884. (No model.)

To all whom it may concern:

Be it known that I, ADOLPH WEBER, of Detroit, in the county of Wayne and State of Michigan, have invented new and useful Improvements in Straight-Way-Valve Cases; and I do hereby declare that the following is a full, clear, and exact description thereof, reference being had to the accompanying drawing, which forms a part of this specification.

10 This invention relates to certain new and useful improvements in the manufacture of straight-way-valve cases; and the invention consists in the peculiar combinations and the construction and arrangement of parts hereinafter more particularly described, and then pointed out in the claim.

In the accompanying drawing, which forms a part of this specification, a straight-way-valve cage is shown in sectional perspective, 20 in which A represents the cage proper, cast in iron, provided with the usual inlet and outlet passages in line with and directly opposite each other, of the usual and known patterns. The valve-seats B are of brass. 25 These valve-seats consist of flattened brass rings of sufficient width inserted at the inner ends of the inlet and outlet passages, between which the valve ordinarily employed is interposed to cut off the flow of water. In the 30 process of casting, these rings having been previously cast, they are inserted in the mold formed for casting the cage, in the manner well known to molders; and in order to secure a perfect uniting of the iron with the brass, 35 the outer edge face of the ring has formed therein a groove, and there is formed in the outer flat face another groove, b, and the iron entering in the process of casting each of these grooves, a perfect lock between the two metals 40 is formed. Brass fusing at a less temperature than is required to melt iron has in cooling a greater shrinkage than the iron; hence any attempt to cast brass and iron together is futile, for the difference in shrinkage between the 45 two metals would draw them apart and break

the contact. By my process, the brass rings being cold, (and, as before remarked, brass fusing at a lower temperature than iron,) when the hot iron is poured into the mold and comes in contact with the brass rings forming the 50 seats, the contact of the molten iron with the brass has a tendency to partially fuse the contact-face of such brass, and thereby a perfect juncture of the two metals is had, the brass being additionally secured in place to the iron 55 by the locking, as before described.

As it is necessary that the brass rings which form the valve-seats are properly supported in their proper relation to each other and to the water-ways of the case, I reserve the right 60 to file another application upon the process of making the composite straight-way-valve case described in this application.

I am aware of the Patent No. 44,326, and make no claim to the construction shown 65 therein as forming part of my invention. I attach importance to the two grooves arranged at right angles to each other, for by this construction the dovetails formed by the iron entering these grooves draw in opposite directions to each other when the metal shrinks in cooling, thereby more effectually holding the ring in contact with the metal of the cage. By the previous constructions this point of contact almost invariably leaks, whereas mine 75 is always tight. This result cannot be obtained from a single centrally-located dovetail shown in the patent above referred to.

What I claim as my invention is—

A brass ring provided upon its outer edge 80 face with a groove and upon its outer flat face with another groove standing at right angles, or nearly so, to the first-named groove, in combination with a cast-iron valve-case, substantially as set forth.

ADOLPH WEBER.
